COMBINED MULTIPLE SEATING UNIT AND TABLE

George Kasparian, 9562 La Tijera Blvd.,
Los Angeles, Calif.

Filed July 5, 1960, Ser. No. 61,209

Term of patent 14 years

(Cl. D15—1)

Fig. 4

Fig. 5

FIGURE 1 is a perspective view of a combined multiple seating unit and table, showing my new design;

FIGURE 2 is a front elevational view of the multiple seating unit and table shown in FIGURE 1;

FIGURE 3 is a side elevational view thereof;

FIGURE 4 is a rear elevational view thereof; and

FIGURE 5 is a top plan view thereof.

I claim:

The ornamental design for a combined multiple seating unit and table, as shown.
